UNITED STATES PATENT OFFICE.

HARRY W. HILL, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC LENS.

Application filed September 16, 1919. Serial No. 324,087.

To all whom it may concern:

Be it known that I, HARRY W. HILL, a citizen of the United States, residing at Southbridge, in the county of Worcester and State of Massachusetts, have invented certain new and useful Improvements in Ophthalmic Lenses, of which the following is a specification.

This invention relates to improvements in ophthalmic lenses and has particular reference to an improved process for forming such lenses.

A large proportion of ophthalmic lenses are sold in semi-finished condition, that is, the manufacturer grinds a power curve on one side of the blank, leaving the other side unground. The dispensing optician grinds the other side to a curve that in combination with the first curve will give the required prescription. It is important, therefore, that before he does any work of grinding the second side the dispensing optician should know whether or not there are defects such as striae, bubbles, cracks, etc., in the blank which cannot be removed when the second side is ground. If he does not detect these defects the finished lens will be worthless, and he will have thrown away all his work and the cost thereof, and will have to grind another all over again, causing delay to the patient, etc. If both surfaces of the blank are cleared these defects may be readily detected by inspection, simply by holding them up to the light and looking through them.

It is important that the unfinished side be cleared before the power curve side of the blank is ground as there would be a likelihood of injuring the power curve side if the clearing were done afterwards. I, therefore, provide cleared blanks for inspection and a process of making them in large numbers at once and before any grinding is done upon them.

Prior to my invention, in the production of ophthalmic lenses, it has been customary first to mould a lump of glass into a blank of concavo-convex form, and after such moulding to grind and polish the resultant glass blank into a finished lens; that is to say, into a final completed prescription lens or into a lens blank finished in final form on one side and polished to produce trans-

parency though requiring subsequent grinding of prescription curve on the opposite side. This grinding and polishing of the second side of the lens blank, when the glass is to be sold in the form of a blank, is practically necessary in the case of bifocal lenses made from a single piece of glass or of other lenses of high quality which must be inspected through the glass for defects of material or manufacture before the article is placed on sale. This grinding and polishing of the second side is an expensive proposition to the manufacturer as, on account of the short radius of curvature of the surfaces or their strong power, as it may be termed, and the size of the pieces of glass, the grinding and polishing must be done either as an individual job or at the most upon only two or three pieces at a time.

In addition, in the grinding of bifocal lenses for example from the molded glass, it is necessary to remove a considerable amount of stock from the molded blank relatively before all trace of pits and the like produced by molding may be removed, and since this type of grinding is a different operation requiring considerable skill properly to produce the surfaces, this too adds considerably to the cost of manufacture.

It is also a great saving in grinding to mold the blank substantially to the curve that is to be ground on the first surface or power curve side of the blank. As is well known, molding mars and clouds the surface of the glass; hence I bend or mold the blanks over a form on the side on which the first power curve is to be ground, leaving the other side cleared; hence when the first side is ground and polished to curve the blank will have both surfaces cleared.

It is, therefore, the object of the present invention to eliminate these difficulties which have been experienced in the prior art production of lenses and to provide a novel and improved process through the use of which lenses of the most perfect form or forms and ordinarily quite difficult and expensive to manufacture may be produced more rapidly and inexpensively, and cleared blanks therefor which may be made in large numbers at once, readily dropped to

2
form and adaptable for use and ready inspection.

Other purposes and advantages resultant from my improved process should be apparent to those skilled in the art by a reference to the following specification taken in connection with the accompanying drawings, and it will be understood that I may make any modifications in the specific 10 features hereinafter described within the scope of the appended claims without departing from or exceeding the spirit of my invention.

Figure I represents a view diagrammatically illustrating the condition of an ordinary molded blank.

Figure II represents this blank at the completion of certain steps of my process.

Figure III illustrates a further step of 20 the process.

Figure IV illustrates another step therein.

Figure V illustrates a slight modification 25 of the features illustrated in connection with Figure III.

Figure VI illustrates the blank produced from Figure V.

Figure VII illustrates the manner in 30 which my blanks may be prepared, and

Figure VIII illustrates a prior art method.

As mentioned in the preamble to my specification, in the prior art it has been customary to mold blanks into concavo-convex

35 form, such as the shape of the glass blank 1 shown in Figure III of the drawings, this blank having been forced into this form while in semi-molten condition in suitable molds. The disadvantage at present in this

40 process of manufacturing the lenses is that, as is more clearly illustrated in connection with Figure I, when a blank 1 is produced by molding, the surfaces 2 and 3 of the blank are quite rough or pitted due to contact with

45 the mold, and this necessitates considerable grinding and labor before the surface is in finally usable condition. While this is not a serious matter in the manufacture of ordinary spectacle or eyeglass lenses having

50 weak curves or curves of long radius, it becomes a more serious matter in the case of lenses of higher powers, or in other words of shorter radius, and particularly in the case of torics or similar lenses requiring more

55 particular grinding operations properly to produce their surfaces, and is most important in connection with the manufacture of bifocal lenses due to the fact that these lenses are ordinarily produced from blanks

60 of quite large diameter and of relatively strong curve. These combined features make it impossible at one time to surface, grind, or polish more than two or three of these blanks as when finishing up the non-bifocal side it is necessary to grind indi-

vidually the bifocal surface of the glass. This will possibly be best understood by reference to prior art view Figure VIII showing the small number of blanks which can be placed on a substantially hemi-spherical 70 block.

As opposed to these prior art difficulties, by the use of my present improved process I first mold the blank in flat form as shown in Figure I of the drawings and then grind 75 and polish both surfaces of the glass while it is still in plano form, as should be understood by reference to Figure II. In accomplishing this result, substantially any number of blanks may be ground in ordinary 80 plano grinding machines as indicated for example in Figure VII, so that in place of being an individual proposition, large numbers of blanks may be simultaneously produced.

Having thus produced these blanks I drop them by heat softening on suitable molds 4, this softening being sufficient to allow the glass to bend under its own weight but without being reduced to a molten or truly 90 plastic condition, with the result that the upper surface 2 maintains its polished condition, while when the process is properly conducted, the lower surface 3 will show but slight variation from its former polished condition due to contact with the mold. Consequently, but slight work is required to restore the polish on this surface. In this way it is possible to produce a toric curve, for example, on the surface 3, or a bifocal 100 curve comprising the distance portion 5 and reading portion 6, or various types of deformed surfaces may be thus produced, and in many instances it will be found that surfaces thus produced require only polishing as by a polisher 7 to complete the preparation of the semi-finished lens blank. This semi-finished lens blank, on account of the previous polishing of the surface 2, will be entirely transparent to vision, so that the 110 condition of the glass may be readily determined before it is placed on the market.

It will be noted that in Figure V I have shown the production of a blank for bifocal lenses, this form having the mold 8 with the removable center section 9 which may be interchanged to produce various reading portion curves 6 in connection with the same distance curve 5.

In the event that there is any roughness or clouding of the surface 3 of bifocal surfaces 5 and 6 due to the dropping of the blank, I may then grind and polish or smooth and polish this surface or these surfaces in the carrying out of my process, but in place of having to remove the pronounced roughness from molding as customary in the prior art forms there is but a slight amount of glass that must be removed or given surface flow to produce the 120

necessary polish, so that a considerable saving in manufacturing cost is effected through the use of this process.

I claim:

- 5 1. The process of producing a blank for a bifocal lens consisting in polishing a portion of glass in flat sheet form, forming a mold with a major or distance curve portion and a projecting center curve portion, placing the blank supported on the center curve portion and subjecting the mold and blank to gradual heat to cause the blank to subside onto the mold, substantially as illustrated.
- 10 2. The process of producing a blank for a bifocal lens consisting in polishing a portion of glass in a single continuous surface, forming a mold with a major portion having the complement of the curve desired on the distance vision of a bifocal and a central minor portion, having a different curve supporting the blank on the minor portion, subjecting the mold and blank to gradual heat to cause the blank to subside onto the mold, and restoring the polish on the mold engaging surface without altering the configuration produced by the heating effect.
- 15 20 The distance vision portion of a bifocal and a central minor curve portion, supporting the blank on the minor curve portion and

subjecting the mold and blank to gradual heat to cause the blank to subside onto the mold, substantially as illustrated.

25

3. The process of producing a blank for a bifocal lens consisting in polishing a portion of glass in a single continuous surface, forming a mold with a major portion having the complement of the curve desired on the distance vision of a bifocal and a central minor portion, having a different curve supporting the blank on the minor portion, subjecting the mold and blank to gradual heat to cause the blank to subside onto the mold, and restoring the polish on the mold engaging surface without altering the configuration produced by the heating effect.

30

In testimony whereof I have affixed my signature, in presence of two witnesses.

HARRY W. HILL.
